UNITED STATES PATENT OFFICE.

HARMON BROWN, OF TELL CITY, INDIANA.

SCRUBBING-MACHINE.

969,032.

Specification of Letters Patent. Patented Aug. 30, 1910.

Application filed January 28, 1909. Serial No. 474,677.

To all whom it may concern:

Be it known that I, HARMON BROWN, a citizen of the United States, residing at Tell City, in the county of Perry, State of Indiana, have invented certain new and useful Improvements in Scrubbing-Machines; and I do hereby declare the following to be a full, clear, and exact description of the invention, such as will enable others skilled in the art to which it appertains to make and use the same.

This invention relates to scrubbing machines, and has for one of its objects to improve the construction and increase the efficiency, and utility of devices of this character.

Another object of the invention is to provide a simply constructed device whereby a floor may be scrubbed to remove the dirt, and the dirty water together with the cleansing liquid removed and the floor wiped.

The invention consists in certain novel features of construction as hereafter described and shown in the drawings.

Figure 1 is a side elevation of the improved apparatus. Fig. 2 is a plan view of the same. Fig. 3 is a longitudinal section on the line 3—3 of Fig. 2. Fig. 4 is a sectional detail of the reciprocating brush, illustrating its construction.

The improved device comprises an oblong base frame 10, of any suitable material, but preferably of wood, and of any required size. Supported upon one end of the frame 10 is a tank 11 for the cleansing liquid, and for the purpose of this description the end of the frame upon which the tank is located will be referred to as the forward end. The tank is preferably formed with the outer side vertical and the inner side inclined, as shown, whereby a relatively contracted discharge is produced, the discharge provided with numerous relatively small apertures 12, whereby the contents of the tank will be discharged in small fine jets. Movable disposed in the bottom of the tank is a sliding valve 13 whereby the flow from the tank may be controlled or entirely shut off as desired. The valve 13 is provided with an operative rod 14 leading to the rear end of the frame convenient to the hand of the operator, so that the valve can be readily operated from the rear of the machine, as hereafter explained. The frame 10 is mounted upon wheels 15, pref-

erably so arranged that the frame runs as near to the floor as possible.

Formed in the inner faces of the side members of the frame are guideways 16. Extending between the side members 10 is a brush holder formed with a stationary member 17 and a movable member 23; the stationary member 17 being extended at its ends into the guideways 16. The members 17—23 constitute a brush head or holder and the bristles 26 are connected at one end between the brush holder members. The construction of the brush holder is described more fully hereinafter. A rod 18 is connected at one end to the member 17 and extends rearwardly and operates slidably through a transverse guide 19, the latter being supported by the side members 10 of the frame. The rod 18 is provided with diagonal braces 20—21 and with a bottom brace 22, the braces connected at their outer ends to the member 17. By this simple means the brush holder is firmly connected to the rod, and held rigidly in position transversely of the frame. For the purpose of this description the member 17 of the brush holder is referred to as the stationary member, while the member 23 is referred to as the movable member, as the member 23 is caused to move toward or away from the member 17. The member 23 is provided with a longitudinal recess into which the bristles 26 are inserted at their upper ends, and the two members 17—23 coupled by clamp bolts 24—63, the bolts 24 being located above the bristles 26, while the bolts 63 are located at the lower edges of the members 23—17 and extend through the bristles, as shown. The bolt 63 is threaded at one end and provided with a winged head 25 at the other end, so that strain can be applied to clamp the bristles firmly between the members 17—23. By this means also the bristles when worn or impaired can be renewed by simply loosening the bolt 63 and inserting the new bristles and again applying the strain to hold the bristles in position.

The brush head together with the brush elements are adapted to be reciprocated by power applied to the rod 18, as hereafter explained.

Mounted for rotation transversely of the side members of the frame 10 is a rotary brush comprising a central drum 27 having journals engaging in bearings upon the frame, the brush elements 28 being connect-

ed to the drum, as shown. Attached to one of the journals of the rotary brush is a chain wheel 29 to receive the drive chain for operating the brush, as hereafter explained.

5 Mounted for rotation upon the side members of the frame 10 rearwardly of the rotary brush is a drum 30, and mounted for rotation upon standards 31 above the portion of the frame 10 are two rollers 32-33, the rollers provided with bearings 34 whereby they may be compressed toward each other to form a wringing element, as hereafter explained.

15 Swinging upon the side members of the frame 10 are two arms 35-36, and mounted for rotation between the lower ends of these arms is a tension roller 37, the arms operating beneath keepers 38-39 and provided with clamp screws 40-41, so that the arms may be adjusted to any required position within the range of the keepers to adjust the roller vertically as may be required, the object to be hereafter explained.

25 Mounted upon the rear portion of the frame 10 is a tank 42 to receive the water extracted by the wringing element, and to this end the tank is located beneath the rollers 32-33, as shown.

30 Extending around the various rollers 30-32-33-37 is a wiper belt 43 formed of suitable fabric, and to enable the under side of the wiper belt to pass the tank 42 without engaging the same, an idler pulley 35 44 is arranged beneath the belt, as shown. The pulley 37 is so located that its under side may be adjusted through the action of the arms 35-36 to cause the belt 43 to engage the floor indicated at 45. The brackets 40 31 are in the form of rearwardly inclined arms, extending for a considerable distance above the frame 10 and the tank 42, and are connected by a transverse hand grip member 46. One of the bracket members, preferably the one at the right, is provided with a longitudinal slot 47 in which a stub shaft 48 is adjustably supported; the stub shaft carrying a chain wheel 49 and a crank 50. Connected to one of the journals of the roller 50 33 is a chain wheel 51.

Supported upon the frame 10 is a bracket device 53, and mounted for a rotation in this bracket is a short shaft 54 carrying a chain wheel 55 at the outer end and a crank 56 at the other end, the crank connected by a rod 57 to the slidable rod 18, as shown, so that the rotation of the shaft 54 will cause the reciprocation of the rod 18 and the brush connected therewith. The pitman 50 is detachable from the crank 56 to release the brush head 23 from motion when the floor is scrubbed and the brush 26 is to be elevated before rinsing so that it will not touch the floor.

55 An endless chain 58 extends around the

various chain wheels, as shown, so that the belt 23, and brush 27-28 will be rotated and the brush 26 will be reciprocated simultaneously.

The chain wheel 49, which operates as a drive wheel, should be about three times as large as the wheel 29 which actuates the rotary brush, to secure the proper speeds to the various parts, but it will be understood that these dimensions may be varied as required, and it will also be understood that it is not desired to limit the device to any specific dimensions for the wheels.

The belt 43 may be of any suitable material but will preferably be of Turkish toweling material, as experiment has shown that this material answers the purpose admirably.

The tank 11 will preferably be supplied with water having liquid soap material therein when first using the apparatus, and after the floor has been thoroughly scrubbed clean rinsing water may be supplied to the tank and employed to further cleanse the floor.

With a device of the class described, the operation is as follows. The tank 11 being supplied with the cleansing liquid, the machine is moved over the floor and motion imparted simultaneously to the brushes 26-28 and the belt 43, with the result that the brush 26 thoroughly scrubs the floor and removes the dirt and mixes it with water while the rapidly revolving brush 28 throws the dirty water beneath the belt 43 as it passes around the roller 37 and toward the brush 28, the water being picked up by the belt and carried to the wringing element 32-33, where the water is extracted and falls into the tank 42, the cleansed belt then passing to the roller 37 again. This action thoroughly cleans the floor and wipes it dry, and removes the dirt and deposits it in the tank 42 from which it may be removed when required. The rear tank 42 is provided with a receiving chute or hopper 64 and is detachably supported upon the frame 10 and retained in place by hooks 65. The roller 37, as above noted, may be adjusted to increase or decrease the tension of the belt 43 and cause it to bear with any required degree of pressure upon the floor, as will be obvious. The pitman is detachably connected to crank 56 so that it may be removed when it is required to operate the rotary brush 28 independently of the reciprocating brush 26. By this means after the scrubbing action is completed and it is desired to wipe the floor, the pitman 57 is detached and the wing nuts on brush head are loosened to elevate brush 26 free from floor. This is an important feature of the invention and adds materially to its utility and efficiency.

The improved device is simple in construction, can be inexpensively manufac- 130

tered, and operates expeditiously and thoroughly. The operating mechanism is located entirely upon one side of the frame 10, so that the other side may be operated close to the walls of the room, and thus reach every portion of the floor.

The improved device is particularly applicable to the scrubbing of large floors of halls and like rooms, such as depots and the like.

What is claimed, is:—

In an apparatus of the class described, a supporting frame having guideways in its side members, a brush holder comprising a 15 movable member and a stationary member with the stationary member extending at its

ends into the guideways and slidably therein, a guide rod extending from said brush holder, a guide bar extending transversely of said frame and through which said guide 20 rod passes, a shaft mounted for rotation upon said frame and provided with a crank, a connecting rod between said crank and guide rod, and means for rotating said shaft.

In testimony whereof, I affix my signature, in presence of two witnesses.

HARMON BROWN.
